UNITED STATES PATENT OFFICE

2,496,748

APPARATUS FOR TEACHING ACROBATICS

Charles P. Pond, Dallas, Tex.

Application June 12, 1947, Serial No. 754,308

7 Claims. (Cl. 35—29)

1

The present invention relates generally to exercising apparatus and more particularly to apparatus for teaching acrobatics.

The principal object of the present invention is to develop an apparatus for teaching the art of aerial tumbling in all phases, such as forward, backward, side tumbling, twisting, or any other type of tumbling movements.

Another object is to provide an apparatus for teaching acrobatics controlled by the instructor, which while providing safety will also give the student freedom of movement in substantially all directions and whereby as the student becomes more accomplished in the art, the instructor can release his control over the apparatus entirely.

Yet another object is to develop an apparatus of the class above referred to which not only is highly efficient in action, but which is also economical to manufacture, durable and easily repaired.

The above and other objects and novel features of the invention will more fully appear from the following detailed description when the same is read in connection with the accompanying drawings. It is to be expressly understood, however, that the drawings are for purposes of illustration only and are not intended as a definition of the limits of the invention. Reference should be had to the appended claims to determine the limits of the present invention.

In the drawings wherein like reference characters refer to like parts throughout the several views:

Figure 1 is a top plan view of the exercising apparatus with a portion in cross section.

Figure 2 is a general perspective of the apparatus mounted from pulleys in the ceiling of a gymnasium or the like.

Figure 3 is a longitudinal cross section view of the bearings and bearing rings.

Figure 4 is a transverse cross section taken along the line 4—4 of Figure 3.

Referring in detail to the drawings and first with special reference to Figure 2, the apparatus comprises a unit A adapted to be secured around the student's waist and the unit in turn is secured to master control cables 10 and 11, which are strung through pulleys 14 and 15 in the ceiling B of any suitable enclosure. The ends C of the cables are free to be held by the instructor while the student is performing to thereby provide for master control of the student by the instructor at all times during the performance.

More specifically the apparatus comprises a pair of concentrically positioned rings 16 and

2

17. Each of these rings contains a half groove 18 and 19, the outer ring 17 having its groove around its inner side and the inner ring 16 having its groove 19 facing the groove 18, see Figure 4. With the rings thus positioned, there is provided an annular opening in which are mounted a series of ball bearings 20.

The bearings 20 are inserted in the annular opening by way of an opening 21, formed in the rings. This opening is normally closed by one of a pair of diametrically opposite hasp members 23 and 24 to which the cables 10 and 11 are secured. The hasp members comprise a U-shaped base 26 formed with openings adapted to receive bolts 27, to thereby secure the same to the outer ring 17.

Riveted at spaced intervals to the inner ring 16 are radial straps 30 with intermediate buckles 31 for adjustment purposes. Each of these straps 20 are alike and lead to a center belt 32 within the confines of the rings 16 and 17. The belt 32 is made with a buckle or fastener 33 for adjustment to the waist of the student to use the apparatus. Also, further adjustment to the student's waist is provided for by the buckles 31 on the radial straps 30.

In operation, when the belt 32 and radial straps 30 have been adjusted to fit the student and the cables 10 and 11 are in position through the ceiling mounted pulleys, the instructor will grasp the free ends of the control cables at C. The instructor, however, at this stage permits the cables 14 and 15 to be slack to run through the pulleys and merely prepares to pull on the cables 35 if the student appears to be likely to be injured.

Assuming the student is to make a flying aerial twist, he will proceed as though he did not have the apparatus on and as he twists his body to execute the flying twist, the ball bearings 20 will permit the inner ring 16 and its attachments including the student's body to freely swivel in the outer ring 17. Also, if the student is to turn an aerial somersault, then the flexibility of the control cables 10 and 11 at the hasps 23 and 24 will 45 permit freedom of action for this performance.

Thus there is provided an apparatus for teaching acrobatic stunts, which is at all times under the control of an instructor for preventing possible injuries to the students. Also, this apparatus is so arranged that the student's body is free for all motions inside the belt even though the apparatus is controlled by the instructor to protect the student from injury.

Without further description it is thought that 55 the novel features and advantages will be readily

apparent to those skilled in the art, and it will, of course, be understood that changes in the form, proportion and minor details of construction may be resorted to without departing from the spirit of the invention and scope of the appended claims.

I claim:

1. Means for teaching acrobatics controlled by an instructor, comprising, in combination, a unit having a belt adapted to encircle the student's waist, said unit including concentric inner and outer rings, the inner of said rings being connected to the said belt, said inner ring thereby being freely rotatable with the body of the student within the outer of said rings, and instructor controlled cable means secured to the outer portion of said unit and running through ceiling suspended pulleys, the free ends of said cables being manipulatable by the instructor to permit the student to freely turn forwardly, backwardly and twisting either direction while suspended.

2. Apparatus for teaching acrobatics, comprising a unit adapted to be secured to the waist of a student, said unit including an inner belt portion for gripping the waist of the student and an outer portion including a pair of concentric rings rotatably movable with respect to each other, means for connecting the inner ring of said concentric rings to said belt portion, and means on the outer ring for receiving an instructor's suspending connection.

3. Means for teaching acrobatics controlled by an instructor, comprising a unit adapted to encircle a student's waist and permit twisting of the student's body in all directions, and master control cable means secured to said unit and running through ceiling suspended pulleys, the free ends of said cables being manipulatable by the instructor, said unit comprising a belt for encircling a student's waist, a pair of concentrically arranged rings, said inner ring being formed around its outer circumference with a bearing surface and said outer ring being formed around its inner circumference with a bearing surface positioned opposite said bearing surface of the inner ring, bearings mounted on the bearing surfaces permitting turning of the rings relative to each other, means connecting the inner ring to said belt, and means connecting the outer ring to said cables.

4. Apparatus for teaching acrobatics under manual control of an instructor, comprising a pair of concentric rings formed with opposed bearing grooves, ball bearings in the grooves between the rings adapted to hold them together and permit turning of the rings relative to each other, diametrically opposite hasp members secured to the outer of said rings connected to instructor-controlled cables, and radially extending straps secured at one end at spaced intervals to the inner of the rings and at the other end to a belt for encircling the student's waist.

5. Apparatus for teaching acrobatics, comprising a pair of concentric rings formed with opposed bearing grooves, ball bearings in the grooves between the rings adapted to hold them together and permit turning of the rings relative to each other, diametrically opposite hasp members secured to the outer of said rings connected to instructor-controlled cables, flexible means secured at spaced intervals to the inner of said rings and to a belt for encircling the student's waist, and means for adjusting the apparatus to fit the student.

6. Apparatus for teaching tumbling, comprising a unit adapted to be secured to the waist of a student, said unit being made from a pair of inner and outer rings, said inner ring being formed around its outer circumference with a bearing surface and said outer ring being formed around its inner circumference with a bearing surface positioned opposite said bearing surface of the inner ring, bearings mounted on the bearing surfaces permitting turning of the rings relative to each other, said outer ring carrying diametrically opposite hasp members, and instructor-controlled cables secured to said hasps, said inner ring yieldably connecting with an adjustable waist encircling member for the student to wear.

7. Apparatus for teaching tumbling, comprising a unit adapted to be secured to the waist of a student, said unit being made from a pair of inner and outer rings, said inner ring being formed around its outer circumference with a bearing surface and said outer ring being formed around its inner circumference with a bearing surface positioned opposite said bearing surface of the inner ring, bearings mounted on the bearing surfaces permitting turning of the rings relative to each other, said outer ring carrying diametrically opposite hasp members for connection to instructor-controlled cables and said inner ring carrying an adjustable waist encircling member for the student to wear, and flexible means adjustably connecting said waist member to said inner ring.
